UNITED STATES PATENT OFFICE.

ALANSON L. FISH, OF FLUSHING, NEW YORK.

AUTOMATIC TIMING DEVICE.

1,146,320.

Specification of Letters Patent.

Patented July 13, 1915.

Application filed March 18, 1914. Serial No. 825,499.

To all whom it may concern:

Be it known that I, ALANSON L. FISH, a citizen of the United States, residing at Flushing, county of Queens, State of New York, have invented a new and useful Automatic Timing Device, fully described in the following specification and the accompanying drawing, forming a part of the same.

My invention relates to an automatic timing device for foot or other races, and its object is to provide a mechanism which will automatically start a stop-watch at the beginning of a race, and which will automatically stop the watch when the racer crosses the finish line.

With this and other objects in view, the invention consists in certain combinations and parts as will be hereinafter fully described and then specifically pointed out.

Referring to the drawing: Figure 1 is a somewhat diagrammatic view of the complete device, partly in elevation and partly in plan, and showing the electrical connections. Fig. 2 is a plan view of the means for supporting and actuating the stop-watch. Fig. 3 is a side elevation of one of the circuit closing devices shown in Fig. 1. Fig. 4 is a plan view of the other circuit closing device. Fig. 5 is a rear elevation of the device shown in Fig. 3. Fig. 6 illustrates a modification of my device. Fig. 7 is a sectional view on line 7-7 of Fig. 6.

Reference numeral 1 represents the casing for supporting the stop-watch. This casing is adapted to be secured by the clamp 2 to any suitable support 3. The support 3 might, for instance, be a part of the grand stand or of the judges' stand. The stop-watch 4 is held in the casing by the spring clamp 5, which if desired may be made adjustable to receive watches of different sizes. The actuator 6 is pivoted to the casing at 7, and is provided with a projection 8 for engaging the stem of the stop-watch. This actuator is moved by the electromagnet 9 as will be hereinafter described.

Reference number 10 indicates the starter's pistol, to which the member 11 is adapted to be attached. Pivoted to the member 11, at 12, and insulated therefrom is the member 13, 14. The end 14 of this member is enlarged, as shown clearly in Fig. 4, and being heavier than the end 13, is held by gravity against the insulated post 15, as shown in Fig. 1. In this position the enlarged end 14 projects in front of the gun barrel, and the

end 13 is elevated out of contact with the electric terminal 16. At the discharge of the gun, the gases issuing from the gun barrel impinge against the end 14, causing a clockwise rotation of the pivoted member 13, 14 and consequently a contact between the members 13 and 16.

Pivotedly mounted on the rod 17, is the arm 18, held in adjusted position thereon by the collar 19. This arm 18 is formed with a web 20, as shown in Fig. 3. Adjustably secured to the rod 17 below the arm 18, is the member 21, which supports at one end the resilient member or switch 22. This switch normally assumes the position shown in Fig. 5, with the arm 18 in its normal position against the stop 23, as shown in Fig. 1. When, however, the arm 18 is moved in a clockwise direction into the position shown in broken lines in Fig. 1, the web 20 has a camming effect upon the switch 22, forcing it into contact with the electric terminal 24. The arm 18 is adapted to be swung in the manner described, by the body of the racer 80 as he crosses the finish line. This may be effected by so placing the arm 18 that the racer contacts with it directly, or by stretching a comparatively weak cord across the finish line and securing one end of the cord 85 to the arm 18. The instant the racer strikes the cord the arm will be actuated, and then the cord will break so as not to interfere with the progress of the racer. A spring or other suitable means (not shown) may be 90 employed for returning the arm 18 to its normal position.

A wire 25 connects the upper terminal of the electromagnet 9 with a battery or other source of electricity 26. The battery is in turn connected by the wire 27, 28, to the member 13, 14, at the point 29. The terminal 16 is connected to the lower terminal of the electromagnet by the wire 30. Thus, when the gun is discharged, and the member 13 is thereby caused to contact with the terminal 16, the magnet is energized by the electric circuit which may be indicated as follows: 25, 26, 27, 28, 29, 13, 16 and 30. The energizing of the magnet will cause an instant depression of the actuator 6, and a consequent starting of the stop-watch. Because of the excessive weight of the part 14, the member 13, 14 will almost immediately thereafter resume its normal position, 110 thus breaking the electric circuit, deenergizing the magnet, and allowing the actuator 6

to be raised by the spring in the stem of the watch.

The wire 31 leads from the wire 27 to the terminal 24 of the watch stopping device. 5 A wire 32 leads from the other terminal 33 of this device to the lower terminal of the magnet 9. It will be apparent that when the arm 18 is moved by the racer crossing the finish line, as above described, the circuit 10 25, 26, 27, 31, 24, 22, 23, 33, 32 will be completed, and the magnet thereby energized. This energizing of the magnet will again 15 depress the actuator 6, and according to the well known operation of stop-watches will stop the watch.

The electric circuit herein shown is more or less diagrammatic. It is contemplated to install permanently at the race track the circuit including the battery, the electromagnet 20 and the stopping device, and to insert in this circuit, in shunt, several plug sockets for instance at the 100 yard, 220 yard and 440 yard marks, for the reception of a plug connected to the two terminals of the gun 25 attachment. This provides a very flexible device which may readily be adapted for use in races of any length.

When it is desired to obtain the time of each of the individual racers, a corresponding 30 number of watches 4, and casings 1 is provided. The several electromagnets are connected in series in an electric circuit which includes also a source of electricity and the switch on the attachment 11. Thus 35 when the starter's gun is discharged all of the electromagnets are energized and all of the watches are thereby simultaneously started. For stopping each watch independently of the others, each electromagnet is 40 provided with an electric circuit which includes in series, a source of electricity, the two terminals of the electromagnet, and a stopping switch 22. It is understood that there are provided a number of rods 17 cor- 45 responding with the number of racers, and stop-watches, and that each such member 17 supports a switch 22, an arm 18, etc. The arms 18 are arranged so that each of them is actuated by a different racer at the finish 50 line. Thus it seems that when any racer crosses the finish line, the corresponding arm 18 is actuated, the corresponding switch 22 is closed, and the corresponding watch 4 is stopped. In this way the time of each in- 55 dividual racer is recorded.

In the modification illustrated in Figs. 6 and 7, the electrical starting device including the electromagnet 9, the battery 26, attachment 11, etc., remain unchanged. But 60 the electromagnet is not utilized for stopping the watch, this function being performed by a mechanical device which will now be described. The hollow cylinder 35 is attached to a supporting member 36, 65 which is provided with a suitable clamp 2'.

Within the cylinder is the rod 27. Surrounding this rod is a spring 38, the lower end of which abuts against the shoulder 39 held in position on the rod 37 by the pin 40, and the upper end of which abuts against the upper head 41 of the cylinder. Thus the rod is normally forced in a downward direction. Secured to the upper end of the rod 37 is the rod 42 of spring material. The latch 43 is adjustably secured to the rod 42. Secured to the holding member 36, or to some suitable part of the cylinder 35, is the member 44 provided at its upper end with two inclined surfaces 45, 46, as clearly shown in Fig. 6. As the rod 42 is raised from its normally depressed position the surface 45 cams the member 43 and the spring rod 42 to the right as viewed in Fig. 6 until the member 43 passes beyond the said surface, when the rod 42 and member 43 spring back to the left assuming the position shown in full lines in Fig. 6. As a result the latch 43 is locked in elevated position by the inclined surface 46, the spring 38 being compressed. The holder 1 and the cylinder 35 are clamped to the rod 17 by the clamps 2, 2', in such position that when the latch 43 is locked over the member 44, the lower end of the rod 37 will contact with the actuator 6, and the upper end of the rod 42 will be in the path of the web 20 of the arm 18. Thus when the arm 18 is actuated by the racer crossing the finish line, the latch 43 will be moved off of the surface 46, (see dotted lines in Figs. 6 and 7) and the consequent expansion of the spring 38 depresses the rod 37 thus causing the actuator 6 to stop the watch.

When this mechanical stopping device is employed it is a simple matter to provide for the timing of the several racers in a single race. In doing this, a number of devices 17 corresponding to the number of racers is employed, each device being provided with a holder 1 with its stop-watch, and a device 35 arranged as shown in Fig. 6. The electromagnets of the several holders are connected in series in the electric circuit which includes the switch on the attachment 11. When this switch is closed, therefore, by the discharge of the starter's gun, all of the electromagnets are energized and all of the stop-watches are started. The watches will, however, be stopped independently, the stopping of each watch depending upon the time at which the corresponding arm 18 is actuated by the corresponding racer crossing the finish line. In installing the permanent circuit when the mechanical stopping device is to be used, the wires leading to the switch 22 for the electrical stopping device are of course omitted.

The invention is not limited to the particular embodiment shown and described herein, but obviously many changes may be made therein without departing from the spirit of the invention.

What I claim is:

1. In a device for controlling a stop watch, an actuator for said watch; and means operable by the gases issuing from a gun, when discharged, for controlling said actuator.
2. In a device for controlling a stop watch, an actuator for said watch; means operable by the gases issuing from a gun, when discharged, for controlling said actuator; and additional means for controlling said actuator.
3. In a device for controlling a stop watch, an actuator for said watch; means operable by the gases issuing from a gun, when discharged, for controlling said actuator; and additional means, operable by a passing racer, for controlling said actuator.
4. In a device for controlling a stop watch, an actuator for said watch; an electromagnet for moving said actuator; and an electric circuit for energizing said magnet; said circuit including a plurality of switches any one of which is adapted to close said circuit; one of said switches being attachable to a gun, whereby the switch is closed by the gases issuing from the gun when discharged.
5. In a device for controlling a stop watch, an actuator for said watch, an electromagnet for moving said actuator; and an electric circuit for energizing said magnet; said circuit including a plurality of switches any one of which is adapted to close said circuit; one of said switches being attachable to a gun, whereby the switch is closed by the gases issuing from the gun when discharged; and another of said switches being adapted to be closed by a passing racer.
6. In a device for controlling a stop watch, an actuator for said watch; an electromagnet for moving said actuator; and an electric circuit for energizing said magnet; said circuit including a switch adapted to be closed by the gases issuing from a gun when discharged.
7. In a device for controlling a stop watch, an actuator for said watch; an electromag-
- net for moving said actuator; and an electric circuit for energizing said magnet; said circuit including a fixed terminal and a movable terminal; said movable terminal being positioned so that it is moved into contact with the fixed terminal by the gases issuing from a gun when discharged.
8. In a device for controlling a stop watch, an actuator for said watch; an electromagnet for moving said actuator; and an electric circuit for energizing said magnet; said circuit including a switch adapted to be attached to a gun in such a way that a part of said switch overlies the end of the muzzle of the gun, whereby said switch is closed by the gases issuing from the muzzle when the gun is discharged.
9. In an electric timing device, an electric circuit, and a circuit closer included in said circuit and adapted to be operated by the gases issuing from a gun when discharged.
10. In an electric timing device, an electric circuit, including a fixed and a movable terminal, said movable terminal being positioned so that it is moved into contact with the fixed terminal by the gases issuing from a gun when discharged.
11. In an electric timing device, an electric circuit and a circuit closer included in said circuit, said circuit closer being adapted to be attached to a gun in such a way that one member thereof overlies the end of the muzzle of the gun, whereby the circuit closer is operated by the gases issuing from the muzzle when the gun is discharged.
12. In an electric timing device, an electric circuit, a circuit closer included in said circuit and adapted to be operated by the gases issuing from a gun when discharged, and a second circuit closer included in said circuit and adapted to be operated by a passing racer.
